UNITED STATES PATENT OFFICE.

JOHN W. GORDON, OF SPRINGFIELD, ILLINOIS.

CARPET-CARRIER FOR SEWING-MACHINES.

SPECIFICATION forming part of Letters Patent No. 739,856, dated September 29, 1903.

Application filed April 9, 1903. Serial No. 151,812. (No model.)

To all whom it may concern:

Be it known that I, JOHN W. GORDON, a citizen of the United States, residing at Springfield, in the county of Sangamon and State of Illinois, have invented certain new and useful Improvements in Carpet-Carriers for Sewing-Machines, of which the following is such a full, clear, and accurate description as will enable others skilled in the art to which it appertains to make and use my said invention.

My invention relates to apparatus for carrying carpet and guiding it through a sewing-machine during the operation of sewing the carpet, the sewing-machine being stationary and the carpet moving through the sewing-machine.

The purposes of my invention are to provide a carpet-carrier adapted to support the matched edges of carpet to be sewed, the carpet being held by gravity in contact with a gage or guide on the sewing-machine in position to be fed horizontally through the sewing-machine by the feed device of the sewing-machine; to provide means for connecting the carpet with the carrier-frame, so that the weight of the carpet will serve to keep the edges of the carpet which are to be united by the seam in uniform contact with the gage guiding the movement of the carpet through the sewing-machine; to provide means for stretching the carpet on the carrier-frame; to provide means for counterbalancing the weight of the carrier-frame and the carpet carried thereon, so that the feed device of the sewing-machine with which the carpet-carrier is used will substantially suffice to propel the carrier-frame and feed the carpet through the sewing-machine; to provide a track and supporting structure of novel and improved construction; to provide a carrier-frame of novel and improved construction, and to provide a gage of novel and improved construction adapted to turn toward each other the edges of the carpet being sewed, so that the needle will go through the edges of the carpet slantingly and draw the edges together instead of sewing through and through the carpet and also adapted to press the pile outward between the edges of the carpet, so that the pile will not be caught in the seam.

With these ends in view my invention consists in the novel features of construction and

combinations of parts shown in the annexed drawings and hereinafter particularly described, and finally recited in the claims. 55

Referring to the drawings, Figure 1 is a perspective view of the complete apparatus and shows in outline a sewing-machine in operative relation to the apparatus. Fig. 2 is an enlarged transverse section on the line 22 60 of Fig. 1. Fig. 3 is an enlarged perspective view of the carpet-gage, and Fig. 4 is a vertical section on the line 4.4 of Fig. 3.

Similar reference-letters designate like parts in all of the views. 65

My carpet-carrier may be used with any ordinary sewing-machine, straight or zigzag, without any change in the sewing-machine and without interfering with the use of the sewing-machine for other purposes. 70

The apparatus is primarily intended for use in sewing carpets, but obviously may be used in sewing other fabrics too heavy to be conveniently manipulated by hand, such as tents, awnings, &c. 75

The carrier-frame A is preferably made of gas-pipe and has horizontal members a, vertical members a', and brace members a², all separably connected by suitable couplings a³ to form a frame, substantially as shown. 80 Truss-rods a⁴ give rigidity to the frame. Grooved wheels A⁵ are journaled on the upper end of standards A⁴, which are suitably secured to the frame A.

The carrier-frame is made in separable sections, as described, for convenience in handling and packing same for transportation and storage. A grooved wheel or spool A⁵ is secured to the shaft of a crank A⁶, which is mounted to turn in suitable bearings on one 90 of the members a'. A ratchet-wheel A⁷ on the crank-shaft is engaged by a pawl A⁸ to prevent the shaft from turning backward. A clip a⁵ or other suitable hook or catch for holding the edges of the carpet C is connected 95 with one of the members a', and a similar clip is connected with the spool A⁵ by a cord a⁶, so that when the clips have hold of the carpet the turning of the crank will wind the cord on the spool, so as to stretch the carpet 100 between the clips, and the pawl will hold the spool and keep the carpet stretched. Arms A⁹, secured to the frame, project rearwardly at right angles to the frame. Cords a⁷, se-

cured to the outer ends of the arms A³, have at their lower ends clips a⁸, which engage on and hold the carpet. On the cords a⁷ are keys a⁹ for shortening or lengthening the hitch of the cords, so as to adjust the height of the carpet above the floor.

The track B is supported on brackets B'. The wheels A³ travel on the flange-plate b of the track B. This construction permits slight 10 oscillation of the carrier-frame under the track. In practice the carrier-frame runs slightly out of plumb, so that the carrier-frame and its load gravitate to keep the stretched edges of the carpet being sewed in 15 uniform contact with a gage on the sewing-machine used with the apparatus.

A stationary bracket D has near its front end a swivel-block d, carrying a sheave d'. A cord D' has one end secured to the bracket 20 D. The cord passes around the sheaves d' and d², and the other end of the cord is secured to the frame A. A weight d³ is suspended from the sheave d². The weight d³ is adapted to counterbalance the frame A and 25 its load, so that very light pressure will suffice to move the frame in either direction on the track. A spring or other suitable counterbalancing device may be substituted for the weight without departing from my invention.

In the drawings I have shown brackets for supporting the track and the tackle carrying the weight d³. These parts may, however, be supported by rods suspended from the 35 ceiling of a room or by any other suitable support without departing from my invention.

The gage E has a concave inner surface e, an upturned lip e', and a slotted extension e². 40 A corrugated V-shaped wheel E' turns loosely on a vertical pin e³. The wheel E' serves to press the pile out from between the edges of the carpet in sewing pile carpets, as herein-after explained. The gage is connected with 45 the sewing-machine in the usual manner by a screw passing through the slot in the extension e².

The operation of the apparatus is as follows: The widths of carpet to be sewed are 50 first placed face to face and the figures carefully matched. The ends of the matched edges of the carpet are then securely caught in the clips a⁵, respectively. The crank A⁶ is then turned to wind the cord a⁶ on the 55 spool A⁵, thereby tightly stretching the edges of the carpet, as already described. The clips a⁸ are then fastened on any convenient part of the carpet, and the keys a⁹ are adjusted so that the cords a⁷ will support the 60 carpet at the desired height. The gage E is then adjusted on the sewing-machine F, and the sewing-machine is secured in such position that its feed will be parallel to the line of travel of the carrier-frame, and the surface 65 e of the gage will be a little bit behind the line of travel of the carrier-frame in order that the weight of the carrier-frame and its

load will tend to press the stretched edges of the carpet against and keep them in uniform contact with the inner surface e of the gage, thereby uniformly pressing the edges together, so that in sewing the needle instead of passing the thread through and through the fabric will pass the thread slantingly through both of the incurved edges, thereby forming a seam which will lie flat when the carpet is spread. This feature of producing incurving of the edges of the carpet by means of the pressure of the weight of the carrier-frame and the carpet supported thereon against the concave surface of the gage is of great practical advantage and is of the essence of my invention. The carpet being matched, stretched, and swung and the sewing-machine and gage being set as described, the sewing-machine is started, whereupon the feed of the sewing-machine will feed the carpet through the sewing-machine and assisted by the weight d³ will propel the carrier-frame on its track.

When the carpet is of greater length than can be stretched on the carrier-frame at one stretching, one section or part of the length of the carpet may be stretched and sewed and then the next section, and so on until the 95 whole is completed. It will be seen, therefore, that with a short carrier-frame—say twelve or fourteen feet in length—a seam of any length may be sewed by making repeated hitchings of the carpet on the carrier-frame.

In sewing carpets having no pile or very light pile the wheel E' is unnecessary and may be detached by removing the pin e³.

In sewing heavy pile carpets I prefer to use a gage having a serrated wheel E'. Such a gage not only incurves the edges of the carpet, so as to produce a slanting seam, but also presses the pile out between the edges of the carpet, so that practically no pile is caught in the seam. This feature is new and of great practical advantage in producing a seam which does not mar the face of pile carpet.

In sewing straw matting or very light carpet, for which a very flat seam is desirable, I stretch very tightly the edges of the carpet 115 to be sewed together and run the sewing-machine with a comparatively loose tension, so as to produce a seam which catches only on the edge of the carpet or the selvage of the matting, so that when the carpet or matting 120 is laid the stitches will spread, so that the wear will come on the edge of the carpet or matting and not on the thread of the seam.

Having fully described my invention, what I claim as new, and desire to secure by Letters 125 Patent, is—

1. In an apparatus of the class described, the combination of a carrier-frame having horizontal members, vertical members, brace members and rearwardly-projecting arms; 130 standards secured to said carrier-frame, grooved wheels mounted on said standards, a crank-shaft mounted on one vertical member of said carrier-frame, a spool and a ratchet-

wheel secured on said crank-shaft, a pawl engaging with said ratchet-wheel, a cord winding on said spool, a clip connected with said cord, a clip connected with the other vertical member of said carrier-frame, cords secured to the outer ends of the rearwardly-projecting arms of the carrier-frame, clips at the lower ends of said cords, keys on said cords, a track on which said carrier-frame travels, brackets supporting said track, a sheave mounted on a stationary support, a cord running in said sheave and having one end connected with said carrier-frame, and a weight suspended by said cord and gravitating to

15 propel said carrier-frame, as set forth.

2. In an apparatus of the class described, the combination of a track, brackets supporting said track, a carrier-frame having vertical members and rearwardly-projecting arms, 20 grooved wheels mounted on said carrier-frame and traveling on said track, said carrier-frame being mounted to oscillate under said track,

cords secured to the outer ends of said rearwardly-projecting arms and provided with clips, carpet-stretching devices at the lower 25 ends of the vertical members of the carrier-frame, a sewing-machine in operative relation to said carpet-carrier, a gage on said sewing-machine in the line of travel of said carrier-frame, the position of said gage being 30 such that the carrier-frame and its load will gravitate to hold the edges of the carpet stretched between the vertical members of the carrier-frame, in uniform contact with said gage, and a gravitating weight connected 35 to propel said carrier-frame on said track, as set forth.

In witness whereof I have hereunto subscribed my name, at Springfield, Illinois, this 14th day of March, 1903.

JOHN W. GORDON.
